UNITED STATES PATENT OFFICE.

FRANK SOLEY, OF PHILADELPHIA, PENNSYLVANIA, ASSIGNOR TO THE YALE & TOWNE MANUFACTURING COMPANY, OF STAMFORD, CONNECTICUT, A CORPORATION OF CONNECTICUT.

COMBINATION PADLOCK.

Application filed July 20, 1926. Serial No. 123,647.

My invention relates to certain improvements in combination locks, especially locks having elongated shackles, although certain parts of the invention can be applied to 5 swivel shackles as well.

In the type of lock having a long shackle, the casing is perforated for the passage of the shackle therethrough.

One object of the invention is to so design the mechanism that the shackle can be inserted freely at one end of the lock but cannot be inserted in the casing at the opposite end of the lock.

The invention further relates to certain improvements in the locking-bolt for locking the shackle to the casing, and also to the particular stop mechanism used to prevent the entire withdrawal of a shackle in a lock of the sliding shackle type.

20 In the accompanying drawings:

Fig. 1 is a view showing my improved combination padlock in connection with an elongated shackle;

Fig. 2 is an enlarged face view with the 25 cover-plate removed and the bolt engaging the shackle;

Fig. 3 is a view similar to Fig. 2, showing the bolt withdrawn, the shackle being free to be removed;

30 Fig. 4 is a sectional view on the line 4—4, Fig. 2;

Fig. 5 is a sectional view on the line 5—5, Fig. 2, showing the shackle in full lines;

35 Fig. 6 is a view similar to Fig. 5, but showing the shackle inserted in the bottom of the lock and the stop interfering with the insertion of the shackle;

Fig. 7 is a detached perspective view of the bolt-carrying lever;

40 Fig. 8 is a detached perspective view of the bolt;

Fig. 9 is a detached perspective view of the dog;

45 Fig. 10 is a detached perspective view of the casing through which the shackle extends;

Fig. 11 is the stop for preventing the insertion of the shackle from the wrong end of the lock;

50 Fig. 12 is a detached view of the spring for yieldingly holding the stop in position;

Fig. 13 is a view illustrating the mecha-

nism as applied to a lock having a swivel shackle; and

Fig. 14 is a view illustrating a modification of the means for preventing the insertion of the shackle into the casing in the wrong direction.

1 is the casing of a lock, which is cylindrical in the present instance and consists of a back-plate 2 and an integral flange 3, which latter in the present instance is rolled over at 4 upon the cover-plate 5. This cover-plate has a lug 5^a which enters a recess 3^a in the body portion to prevent the cover-plate from turning on the casing. Other means of fastening the cover-plate to the casing may be devised without departing from the essential features of the invention.

Within the casing in the present instance is a bottom plate 6, having a spindle 7, on which are mounted tumblers 8 and spacing washers 9. A coil-spring 10 on the spindle yieldingly holds the tumblers and washers in position. A knob 11, mounted in the 70 casing, is secured to a notched disk 12, and this disk actuates the tumblers. The knob has a pointer 13, and on the cover-plate is a dial 14, clearly shown in Fig. 1. Mounted on the spindle 7 is a carrying-lever 15, having a pivot pin 16, on which is mounted a bolt 17 having a nose 18 which is arranged to enter any one of the notches 19 in the shackle 20. On the bolt is a pin 21, and one arm of a spring 22 which is mounted 80 on the pin 16, bears against the pin 21, while the other arm bears against the fixed portion of the lock. This spring tends to yieldingly hold the bolt in locked position.

The shackle 20 is of the long-leg type, 90 and both legs are notched so that the shackle can be reversed in order that the nose 18 may engage either of the series of notches, but it cannot be inserted into the lock from the bottom, as the end of the leg of the shackle will strike a stop 23, adapted to a slot 24 in a casing 25. One of the legs of the shackle extends entirely through this casing as shown in Fig. 2. The stop 23 is beveled at 26, as shown in Figs. 5 and 11, to 100 allow the shackle to be inserted through one end of the lock casing. The stop 23 is held yieldingly in position by a spring 27, secured at 28 to the casing 25.

On the lower end of the bolt-carrying lever 15 is a projection 29, which is engaged by an arm 30 on a dog 31, which is pivotally mounted on a pin 32 secured to the bottom plate 6. A spring 33 tends to force the portion 34 of the dog against the edges of the tumblers 8, and when all of these tumblers are moved to a certain position, all of the notches of the tumblers are in alignment, and the spring 33 will force the portion 34 of the dog 31 into the notches and thus release the bolt-carrying lever from the control of the dog, so that the lever will move the bolt to the position shown in Fig. 3, in order that the shackle can be withdrawn.

A stop-pin 35 limits the movement of the lever 15 in one direction, while the arm of the dog limits it in the opposite direction. The upward movement of the bolt is limited by a stop 36 on the lever, this stop in the present instance being bent from the lever as shown in Fig. 7.

By the foregoing, it will be seen that the bolt will yield for the insertion of the elongated shackle to any position desired, and the shackle will be locked against withdrawal until the bolt is retracted as in Fig. 3. The stop 23 does not interfere with the longitudinal movement of the shackle when it is inserted in the right direction, but should the shackle be inserted from the bottom, then the stop will interfere with the movement of the shackle and thus prevent the insertion of the shackle into the wrong end of the lock casing.

In Fig. 13 I have shown a lock having a swivel shackle, and the long leg of the shackle in this instance has a shoulder 37 which is engaged by the stop 23 and limits the longitudinal movement of the shackle, but allows the shackle to be turned freely in the casing when released from the locking mechanism.

In some instances, in place of using the stop illustrated in Fig. 11, the stop shown in Fig. 14 may be used, which rests normally in the path of the shackle, and which would prevent the insertion of the shackle at the wrong end of the casing but allow the shackle to be freely inserted in the opposite end of the casing.

By mounting the locking mechanism on the bottom plate, the mechanism can be assembled complete and then inserted in the casing.

I claim:

1. The combination in a padlock, of a cas-

ing; a shackle adapted to the casing; a pivotally mounted bolt-carrying lever; a bolt pivotally mounted thereon; a dog arranged to hold the bolt in the locked position; tumblers acting in conjunction with the dog; and means for actuating the tumblers to move them into locked or unlocked position. 65

2. The combination of a casing having through openings; an elongated shackle having two notched arms; a shackle casing secured to the lock casing; a yielding stop extending into the opening of the casing so as to allow the insertion of the shackle into one end of the lock but preventing the insertion of the shackle into the opposite end of the lock; and locking mechanism arranged to engage the other arm of the shackle. 75

3. The combination of a lock casing having through openings; a bottom plate mounted in the casing; a spindle secured to the bottom plate; a bolt-carrying lever pivotally mounted on the spindle; a pivoted bolt carried by the lever and having a nose arranged to engage one of the notches of the shackle; a spring tending to yieldingly hold the bolt in engagement with the shackle; a dog having an arm bearing against a projection on the lever; tumblers controlling the position of the dog; and means for actuating the tumblers. 80

4. The combination of a casing; a notched shackle; a shackle casing located within the lock casing and adapted to receive one leg of the shackle, said shackle casing being slotted; a stop located in the slot and extending into the path of the shackle; and a spring tending to hold the stop in position, 95 said stop being arranged to engage the shackle.

5. The combination in a lock, of a casing; a spindle in the casing; a bolt-carrying lever pivotally mounted on the spindle and having a projecting stop; a stop-pin on the casing to limit the movement of the lever in one direction; a bolt pivotally mounted on one end of the lever and having a beveled nose, said bolt arranged to engage the stop on the 105 lever; a spring tending to yieldingly hold the bolt against the stop; a dog having an arm; a projection on the lever located in the path of the arm; notched tumblers on the spindle arranged to be moved into and out of position; means for moving the tumblers; and a notched shackle extending into the lock casing and arranged to be engaged by the nose of the bolt. 110

FRANK SOLEY.
